[57] CLAIM

The ornamental design for a plastic bag holder, as shown and described.

DESCRIPTION

FIG. 1 is a perspective view of our plastic bag holder shown in its operational position. The broken line showing of a plastic shopping bag is for illustrative purposes only and forms no part of the claimed design;

FIG. 2 is a top view of our plastic bag holder shown in its flattened non-operational position;

FIG. 3 is a bottom view of the holder as shown in FIG. 2; FIG. 4 is a right side elevational view of the holder as shown in FIG. 2, with the left side elevational view being a mirror image thereof; and,

FIG. 5 is an end view of the holder as shown in FIG. 2. The broken lines shown on the holder on FIGS. 1, 2, and 3 are representative of fold line.
